Patented May 21, 1957

180,347

PHONOGRAPH TRANSDUCER

John F. Wood, Buchanan, Mich.

Application May 26, 1955, Serial No. 36,240

Term of patent 14 years

(Cl. D26—14)

Fig. 3.

Fig. 4.

Fig. 1.

Fig. 2.

Figure 1 is an elevational front view of a phonograph transducer, showing my new design;

Figure 2 is a left side elevational view; the right side being similar but oppositely arranged;

Figure 3 is a top plan view; and

Figure 4 is a bottom plan view.

I claim:

The ornamental design for a phonograph transducer, as shown.
